UNITED STATES PATENT OFFICE.

YUJI YAMANOUCHI, OF KYOTO, AND KAZUYOSHI HIRABARA, OF OSAKA, JAPAN.

DRILL-HEAD-HAMMERING DEVICE.

Application filed January 17, 1924. Serial No. 636,869.

To all whom it may concern:

Be it known that we, YUJI YAMANOUCHI, a subject of the Emperor of Japan, residing at No. 164 4-Chome, Kiyomizu, Shimokyo-
5 Ku, city of Kyoto, Empire of Japan, and KAZUYOSHI HIRABARA, a subject of the Emperor of Japan, residing at No. 71-C, 3-Chome, Hondencho-Dori, Nishi-Ku, city of Osaka, Empire of Japan, have jointly invented certain new and useful Improvements in Drill-Head-Hammering Devices, of which the following is a specification.

The present invention relates to drill head hammering devices and the features of this 15 invention are particularly well adapted for rock drills. This invention is characterized by the feature that the hammering member is held freely movable between a pair of guide plates, each plate having an arc-shaped slot by which the hammering member is guided.

The object of this invention is to provide simple and effective construction which will transmit a strong shock to a hammer head 25 with smooth rotation, and by which the undesirable shock to the driving shaft due to the swinging down of the hammering member can be greatly reduced.

In the accompanying drawings:—
30 Fig. 1 is a side view of a rock drill embodying this invention, a portion of which is broken away to show the inner parts;

Fig. 2 is a plan view of same, a portion of which being broken away;

35 Fig. 3 is a vertical sectional view of an essential part, and

Fig. 4 illustrates the moving conditions of the hammering member.

The same reference numerals represent 40 the same or similar parts.

Referring to the drawings, a rotating or driving shaft 2 is mounted on a suitable frame work 1 and is adapted to be rotated by an electric motor or other prime movers 45 through a flexible shaft 3. The shaft 2 has fixed on it an eccentric disc, or circular enlarged portion 4 which is eccentrically located so as to have a similar construction as an eccentric, two guide plates 5 being 50 fixed to said portion. These plates are composed of projecting portions 5' extended from one side of a boss 5 and annular flanges 5" extended from the opposite inner side of said boss. The circumferential extent of 55 flanges 5" is shown by broken lines in Fig. 4. When said portions 5' and flanges 5" are

fixed on to the shaft in an opposite relation, some space should naturally be left between two guide plates 5 by the present construction. An arc-shaped slot 6 is provided on 60 each of said projecting portions 5' and disposed radially. 7 indicates a somewhat cylindrical hammering member, the lugs 8 of which are guided by said slots. By this arrangement the hammering member can be 65 held between the guide plates in a free floating relation.

By thus rotating the shaft 2, the hammering member is shifted to the outer extremity 70 of the slot by its centrifugal force, as shown in Fig. 4^A, and when it strikes against the end of hammer head 9 which is supported on the frame, the hammering member will swing down along the slot and retract to the inner extremity of the slot, owing to 75 the combined action of the reaction of the striking and the direction of rotation of the guide plates, as shown in Fig. 4^B, and pass over the hammer head after giving a striking to it, and then again proceed to the outer 80 extremity of the slot due to centrifugal force and ready for another striking, as shown in Fig. 4^C.

As the hammering member thus moves in its arc-shaped passage, the rotating shaft is 85 very slightly affected by the shock and movement of the hammering member. Moreover, by the arrangement according to this invention the shock on the shaft when the hammering member swings down and strikes 90 against the shaft can be greatly reduced; the slotted surface of an enlarged portion of rotating shaft between guide plates constituting the shock damper, said member will 95 strike against the surface mildly, and the shock given to the hammer head is transmitted to a drill 10 which is fitted in contact with said head.

If it is required in some instances to rotate the drill after each knock, as for instance in the case of a rock drill, the driving shaft 2 may have eccentric discs fixed on it or circular disc 11 fixed to the enlarged portion of the shaft and eccentric rod 12 connected to an eccentric strap surrounding said disc to swing a forked rod 13 according to the rotation of the main shaft, a pawl which is mounted on the forked portion of the rod 13 is engaged with a toothed wheel 14 which is fixed to the drill 10. Thus the drill 10 100 can be revolved after each shock.

The arrangement according to this inven-

tion as above described has an advantage of giving heavy striking on the hammer head with less shock and effect to the shaft due to the shifting of the hammering member 5 which on the contrary will cooperate and assist the rotation of the shaft. Accordingly, the smooth operation is obtained and the irregularity of motion which is subjected in almost all of such kinds of apparatuses 10 can be greatly reduced and moreover it is simple in construction.

Having now described our invention, we claim:—

1. In a drill head hammering device, the 15 combination with a substantially cylindrical hammer member having end lugs, of a pair of guide plates having arc-shaped slots radially disposed and arranged to guide said lugs of the hammer member, and a driving 20 shaft for said guide plates.

2. In a drill head hammering device, the 25 combination with a substantially cylindrical hammer member having end lugs, of a pair of guide plates provided with projecting extensions having arc-shaped slots radially dis-

posed and arranged to guide said lugs of the hammer member, and annular flanges oppositely located to said projecting extensions arranged to hold said guide plates apart and a driving shaft for said guide 30 plates.

3. In a drill head hammering device, the combination with a drill and a substantially cylindrical hammer member having end lugs, of a pair of eccentric guide plates having radially disposed arc-shaped slots arranged to guide said lugs of the hammer member, a driving shaft for said eccentric guide plates and means to rotate said drill successively, said means consisting of an eccentric disc mounted on said driving shaft, a forked rod secured thereto, a pawl mounted on the end of said forked rod and a toothed wheel fixed to said drill and arranged to be engaged by said pawl for every 40 45 rotation of said driving shaft.

Signed at the city of Kobe this 27th day of Dec. 1923.

YUJI YAMANOUCHI.
KAZUYOSHI HIRABARA.
